WIREBOUND CONTAINER

Leslie M. Hile, Benton Harbor, Mich.

Application July 14, 1930. Serial No. 467,927

2 Claims. (Cl. 217—122)

This invention relates to wirebound containers, and more particularly to baskets, or containers which can be used as such.

Generally stated, the object of the invention 5 is to provide a novel and improved construction whereby a wirebound basket is provided, such as a bushel or half-bushel basket.

A special object is to provide an improved construction and arrangement whereby a wire- 10 bound basket of this kind is made from a foldable wirebound box blank, or a blank similar to those for making wirebound boxes, but of such shape and character that, when folded, it produces a downwardly tapered basket or container.

15 It is also an object to provide certain details and features of construction and combinations tending to increase the general efficiency and the desirability of a basket or container of this particular character.

20 To the foregoing and other useful ends, the invention consists in matters hereinafter set forth and claimed and shown in the accompanying drawings, in which—

Fig. 1 is a perspective of a wirebound container capable of use as a basket, as a substitute for an ordinary round bushel or a half-bushel basket, involving the principles of the invention;

Fig. 2 is a vertical section through a plurality of said containers, showing how the empty baskets are nested together for shipment to the users;

Fig. 3 is a fragmentary perspective view, showing the ends of the cleats that interlock at the corners of the container;

Fig. 4 is a view similar to Fig. 1, but showing the basket in process of formation or construction;

Fig. 5 is a plan view, more or less diagrammatic in character, on a smaller scale, showing the blank from which the said basket is made;

Fig. 6 is a view similar to Fig. 1, showing a different form of the invention;

Fig. 7 is a vertical section, on a smaller scale, through the basket shown in Fig. 6.

As thus illustrated, referring to Figs. 1 to 5, inclusive, the wirebound container to be used as a basket comprises side walls 1 and a bottom wall 2, said side walls being tapered downward to provide baskets which will nest together, as shown in Fig. 2 of the drawings. Cleats 3 are secured to the upper edges of the side walls, outside the basket, and cleats 4 are secured to the lower edges of the side walls, inside the basket. These cleats 55 preferably have tongues 5 and grooves 6 which

interlock at the corners of the basket, as shown in the drawings.

An outside binding wire 7 is secured around the cleats 3, and the ends of this wire are twisted together at one corner of the basket. Middle 60 and lower binding wires 8 and 9 are secured around the basket, as shown, directly to the veneer or other material from which the side walls are made, and the opposite ends of each wire are twisted together at one corner of the 65 basket.

The bottom wall 2 may be secured by staples, not shown, to the tops of the cleats 4, or this bottom wall may be unfastened and simply inserted downwardly in the basket to rest removably upon 70 the tops of the cleats. Whether the bottom is fastened in, or left loose, would depend upon the circumstances and particular use desired for the basket.

As shown in Fig. 5 of the drawings, the side 75 walls of the baskets are made from a blank which, when unfolded and in flat condition, is of the shape shown. It will be seen that the upper cleats 3 are longer than the lower cleats 4 and hence that the blank form is, in effect, curved about an 80 axis. However, when the blank is folded in the manner illustrated in Fig. 4 of the drawings, it develops into a square or rectangular basket, so called, because the top of the basket is square or rectangular, and the bottom thereof is square or rectangular. It is obvious, of course, that a 85 square or rectangular basket is more efficient in some ways than a round basket, inasmuch as they can be placed closer together in a box car, or other place, for shipment or for storage. The 90 only lost space, with a square or rectangular basket, is what would occur between the sides of the adjacent baskets, but this space is much less than what occurs when round baskets are placed side by side and on top of each other. The basket 95 shown and described is flat bottomed, and hence baskets of this kind, when loaded, can be stacked one on top of the other. Although the baskets are square or rectangular, they can be nested together as shown in Fig. 2 of the drawings, when 100 empty, for shipment or storage.

If desired, handles 10 can be applied to the opposite sides of the top of the basket, as shown in Fig. 1 of the drawings.

If the bottom 2 is left loose, the basket can 105 be shipped in the flat and set up in basket form by the user.

As shown in Figs. 6 and 7, the construction is similar to that previously shown and described, but in this case the sides are made up of a plu- 110

rality of staves or slats 11, as shown, instead of from one-piece walls, as shown in the other figures of the drawings.

- As shown in the drawings, staples 12 are employed for securing the binding wire 7 to the cleats 3; staples 13 are employed for securing the binding wire 8 to the sheets or walls; and staples 14 are employed for securing the binding wire 9 to the sheets and the cleats 4, previously described.
- 10 The same arrangement of wires and staples, it will be seen, is employed in Fig. 6 and Fig. 7 of the drawings. It will be understood, of course, that these staples are driven through the materials crosswise of the wires, and that the points of
- 15 the staples are clinched on the inner sides of the basket. But the construction shown and described is illustrative of the invention, and the cleats and other parts may have any suitable form or construction, without departing from
- 20 the spirit of the invention.

It will be seen that the upper cleats 3 extend beyond the edges of the side walls, at both ends of each cleat, and that these cleats interlock, thereby in effect forming a continuous and substantially rigid frame around the outside of the top of the basket. This, it will be seen, is obtained by using a blank of the kind shown in Fig. 5 of the drawings, where it will be seen that the cleats 3 extend beyond the edges of the sections 1, at both ends of each cleat, and that the spaces between the sections 1 are tapered toward the axis about which the blank is in effect curved. However, when the blank is folded, these tapered spaces or gaps are closed by the overlapping edges 35 of the side walls, as shown in the drawings, whereby a very strong construction is provided, the binding wire 7 being tensioned around the corners of the rectangular frame formed by the cleats 3, so that the basket is quite rigid and is adapted to be loaded and shipped in the manner 40 of ordinary bushel or half-bushel baskets, one on top of another.

Thus, it will be seen that the invention contemplates a preliminary blank having the side wall sections thereof tapered toward the bottom edge of the blank, and having tapered spaces between these sections, also tapered toward the bottom edge of the blank, whereby the adjacent edges of the sections diverge toward the upper edge of the blank. Notwithstanding the comparatively wide spaces thus provided between the side wall sections, at the upper edge of the blank, no slack is formed in the upper binding wire at the corners of the container, when the blank is folded. Notwithstanding that the edges of the side wall sections are caused to become parallel, and preferably overlapping, in the finished container, it is nevertheless true that the upper binding wire 7 does not have any slack therein, at the corners of the container, for the reason that the cleats 3 form intervening means between the upper binding wire and the side wall sections,

serving to draw the sections toward each other, and serving also to tension the upper binding wire 7 around the corners of the container. These corners, by reason of the formation of the cleats, are sharp and square, and provide sharp corner 80 edges around which the upper wire is bent and tensioned. Thus the invention contemplates, so to speak, means for automatically converting tapered spaces in the blank into straight spaces, and preferably into overlapping parallel edges, 85 whereby the container, having outer upper cleats and inner lower cleats and binding wires, may be made from a flat blank.

What I claim as my invention is:

1. A wirebound blank for use in making a 90 downwardly tapering container of polygonal cross-section, comprising a plurality of flat side wall sections, each of which is tapered toward the bottom of the blank, said sections being arranged in contiguous relation with the wider portions of adjacent sections spaced to a greater extent than the narrower portions thereof, whereby the sections are arranged in a substantially arcuate formation, cleats, one secured to the upper wider portion of each section against that 100 face which is outer in the finished container, and another secured to the lower narrower portion of each section against that face which is inner in the finished container, top and bottom binding wires flexibly securing the sections together, 105 said bottom wire being secured to the outer faces of the sections, and said upper wire being secured to the outer faces of the cleats, whereby the cleats serve to tension the top wire and bring the wider portions of adjacent sections toward each other 110 when the blank is folded, to form a container capable of being nested.

2. A wirebound blank for use in making a downwardly tapering container of polygonal cross-section, comprising a plurality of flat side 115 wall sections, each of which is tapered toward the bottom of the blank, said sections being arranged in contiguous relation with the wider portions of adjacent sections spaced to a greater extent than the narrower portions thereof 120 whereby the sections are arranged in a substantially arcuate formation, cleats, one secured to the upper wider portion of each section against that face which is outer in the finished container, the ends of adjacent cleats being tongue and 125 grooved for interlocking engagement in the finished container, and another secured to the lower narrower portion of each section against that face which is inner in the finished container, top and bottom and intermediate binding wires flexibly securing the sections together, said bottom 130 wire being secured to the outer faces of the sections, and said upper wire being secured to the outer faces of the cleats, whereby the cleats serve to tension the top wire and bring the wider portions of adjacent sections toward each other when the blank is folded, to form a container capable 135 of being nested.

LESLIE M. HILE.
